UNITED STATES PATENT OFFICE.

CHARLES SEYMOUR, OF LITTLE ROCK, ARKANSAS.

STEAM-BOILER SUPERHEATER.

1,222,476.

Specification of Letters Patent. Patented Apr. 10, 1917.

Application filed October 6, 1916. Serial No. 124,163.

To all whom it may concern:

Be it known that I, CHARLES SEYMOUR, a citizen of the United States, residing at Little Rock, in the county of Pulaski and State of Arkansas, have invented new and useful Improvements in Steam-Boiler Superheaters, of which the following is a specification.

This invention relates to improvements in steam boiler superheaters and has particular application to a superheater of the so called "smoke box" type, that is to say, of the type in which the superheating appliances are located in the smoke box of a fire tube steam boiler.

In carrying out the present invention, it is my purpose to provide a superheater of the class described in which the maximum superheating surface may be presented and the heat of the smoke box effectively and thoroughly imparted thereto during the travel of such gases from the tubes to the stack.

It is also my purpose to provide a "smoke box" superheater which will be found especially useful on the steam boilers of locomotive engines and which will be so associated with the steam pipes leading to the cylinders as to superheat the steam previous to the latter entering such pipe, thereby enabling the superheated steam to be delivered to the drive cylinders immediately succeeding the superheating thereof.

With the above and other objects in view, the invention consists in the construction, combination and arrangement of parts hereinafter set forth in and falling within the scope of the claim.

In the accompanying drawings;

Figure 1 is a cross sectional view through the smoke box of a locomotive boiler equipped with a superheater constructed in accordance with the present invention.

Fig. 2 is a fragmentary longitudinal sectional view through the same.

Fig. 3 is an enlarged cross sectional view on the line 3-3 of Fig. 1.

Referring now to the drawings in detail, 1 designates the smoke box of a steam boiler. 50 Leading into the smoke box 1 at the upper end thereof is a steam pipe 2 connected to the steam space of the boiler and arranged in juxtaposition to the smoke box end of the steam pipe 2 is a steam box 3 divided by means of horizontal partitions 4 into steam chambers 5 and 6 and extending

across the steam box 3 below the partition 6 is a vertical partition 7 that divides the steam box into chambers 8 and 9 and arranged in the chambers 8 and 9 respectively are deflector plates 10 having the relatively opposite ends thereof inclined downwardly, as clearly shown in Fig. 1 of the drawings. In open communication with the relatively opposite ends of the chambers 8 and 9 at 65 the lower ends of the respective partitions in said chambers are curved steam conduits 11 that lead to the drive cylinders of the locomotive and are curved to conform to the curvature of the sides of the boiler. Interposed between the conduits 11 and the sides of the boiler respectively are superheaters 12 each in the form of a casting curved longitudinally to conform to the curvature of the conduits and divided into 70 intercommunicating passages by means longitudinally extending curved partitions 13. Alternate partitions 13 terminate short of one end of the casting, while the remaining partitions terminate short of the opposite end of the casting so as to provide the longitudinally extending intercommunicating passages as clearly illustrated in Fig. 1 of the drawings. The outermost passages in the castings of the superheaters are in 75 open communication with the chamber 5, while the innermost passages in the respective castings communicate with the compartments 8 and 9 so that the steam that is superheated in one casting will be delivered 80 to the opposite conduit, as will be readily understood by referring to the arrows in Fig. 1.

At the bottom of each casting are plugs 14 which may be removed to facilitate cleaning of the superheaters.

Arranged in advance of each superheater and surrounding the front part thereof is a guard or hood 15 that acts to maintain the heated gases in contact with the superheater 100 and the conduits for a relatively long period of time.

In practice, the steam from the boiler flows from the pipe 2 through the steam box 3 and traverses the passages formed in the 105 superheaters and is then delivered through the steam conduits 11 to the drive cylinders of the engine.

While I have herein shown and described the preferred form of my invention by way 110 of illustration, I wish it to be understood that I do not limit or confine myself to the

precise details of construction herein described and delineated, as modification and variation may be made within the scope of the claim and without departing from the 5 spirit of the invention.

I claim:

A smoke box superheater comprising a steam box connected to the steam pipe leading from the boiler and to the curved pipe 10 connected to the engine cylinders and formed to provide chambers, and superheaters between the curved pipes and the outside sheet of the boiler and in open com-

munication with said steam box and the pipes in the smoke box and each formed 15 with longitudinally extending curved partitions, alternate partitions terminating short of one end of the casting and the remaining partitions terminating short of the other end of the casting to form intercommunicating passages, said passages forming a circuitous path for the same whereby the latter may be delivered through the curved pipes to the drive cylinders of the engine. 20

In testimony whereof I affix my signature. 25
CHARLES SEYMOUR.

Copies of this patent may be obtained for five cents each, by addressing the "Commissioner of Patents, Washington, D. C."
